US00D990408S

(12) **United States Design Patent** (10) **Patent No.:** **US D990,408 S**
(45) **Date of Patent:** **** Jun. 27, 2023**

(54) **DETACHABLE TRICYCLE BASKET**

(71) Applicant: **Tianjin shengshida Technology Co., Ltd.**, Tianjin (CN)

(72) Inventor: **Shaolin Ni**, Chaoyang (CN)

(73) Assignee: **TIANJIN SHENGSHIDA TECHNOLOGY CO., LTD.**, Tianjin (CN)

(**) Term: **15 Years**

(21) Appl. No.: **29/778,310**

(22) Filed: **Apr. 12, 2021**

(30) **Foreign Application Priority Data**

Jan. 12, 2021 (CN) 202130018370.9

(51) **LOC (14) Cl.** **06-01**
